UNITED STATES PATENT OFFICE.

CHARLIE SPETH, OF PALMYRA, NEBRASKA.

ROAD-GRADING MACHINE.

1,324,526.

Specification of Letters Patent.

Patented Dec. 9, 1919.

Application filed July 8, 1918. Serial No. 243,959.

To all whom it may concern:

Be it known that I, CHARLIE SPETH, a citizen of the United States, residing at Palmyra, in the county of Otoe, State of Nebraska, have invented certain new and useful Improvements in Road-Grading Machines; and I do hereby declare the following to be a full, clear, and exact description of the invention, such as will enable others skilled in the art to which it appertains to make and use the same.

The present invention relates to road grading machines, more particularly of that type adapted, during progress over a road way, to pick up dirt longitudinally at one portion of the road and to discharge said dirt at another portion of the road to procure a proper crowning of the surface of the road way.

It is in general the object of my invention to simplify, strengthen and otherwise improve the structure and to increase the efficiency of devices of this character.

A feature of the invention resides in the provision in a machine including a plow and a conveying member associated therewith to receive the dirt therefrom, of means whereby said conveying member may be adjusted without affecting the driving operation.

Another feature resides in the provision of a conveying member of exceedingly strong simple structure adapted to receive dirt directly from a plow, and to discharge said dirt at a diametrically opposite point.

With the above and other objects and advantages in view, the invention resides more particularly in the novel combination, formation and arrangement of parts hereinafter described and particularly pointed out in the appended claims.

In the accompanying drawings:

Figure 1 is a plan view of a road grading machine embodying the present invention.

Fig. 2 is a side elevation of the machine.

Fig. 3 is a central longitudinal sectional view through the machine.

Fig. 4 is a transverse sectional view therethrough on the line 4-4 of Fig. 2.

Fig. 5 is a rear elevation of the machine.

Fig. 6 is a detail sectional view taken transversely through one of the table driving shafts on the line 6-6 of Fig. 2.

Fig. 7 is a detail sectional view on the line 7-7 of Fig. 3 through the means for adjusting the turn table.

Fig. 8 is a detail sectional view on the line 8-8 of Fig. 2.

Fig. 9 is a plan view showing an arrangement embodying the use of a pair of turn tables for discharging the dirt a relatively greater distance laterally of the plow.

Fig. 10 is an elevation of what is shown in Fig. 9.

Referring now more particularly to the accompanying drawings, there is provided a main framework comprising side sills 10 convergent toward the front and connected at their forward ends by a journal head 11 in which is mounted a vertical pivot shaft 12 carrying a wheel supporting and steering truck 13 having a draft tongue 14 connected therewith. The rear end portions of the sills 10 are inclined downwardly from the substantially horizontally disposed major portions of said sills and have journaled in their extremities the end portion of an axle 15 having ground wheels 16 mounted thereon. The pivot shaft 12 of the truck 13 is braced below the forward ends of the sills by a journal collar 17 thereon from which arms 18 extend diagonally inward for connection with the sills 10. A sufficiently strong supporting framework is thus provided, the rear ends of these sills being held against relative lateral movement by the shaft 16 or by any other desired means.

Extending inwardly in convergent relation from the forward end portions of the sills 10 is a pair of bars 19 which are connected at their lower ends by a plate 20 which is pivoted between upstanding ears 21 at the forward portion of an annular track frame 22, the axis of these pivotal connections extending horizontally of the machine in a longitudinal direction whereby the track frame 22 may be tilted to raise or depress its portions at the sides of the machine.

For supporting the rear portion of the track frame in a manner permitting such pivotal adjustment thereof, a pair of bars 23 have their lower ends pivoted to upstanding posts 24 at transversely spaced portions of the rear of the track frame and said bars are inclined upwardly toward the rear of the machine. Journaled in standards 25 carried by the sills rearwardly of the upper ends of said bars 23 are shafts 27 which have each fixed thereon a gear wheel 28 whose teeth are in mesh with series of gear teeth 29 on the upper end of the corresponding bar 23. These shafts 27 are swiveled in

100

105

110

alinement at their inner ends in a block 27' and each also carries a hand wheel 30. Thus by rotating the hand wheels, the bars may be raised or lowered to consequently elevate 5 or depress the sides of the track frame 22 to which they are attached, this tilting movement being readily permitted by the three point support provided for the track frame.

10 The periphery of the track frame is provided with a depending flange 31 having an inwardly directed annular track 32 at its lower edge on which are mounted rollers 33 carried by the outwardly extended 15 journaled shafts at the upper ends of brackets 34 upstanding rigidly from a turn table plate 35, which underlies the track frame 22 and which has its diameter considerably greater than the diameter of said track 20 frame whereby the turn table extends outwardly of the track frame. Disposed at one side of the turn table is a plow 36 having its point disposed below the turn table with its mold board overlying the adjacent 25 edge portion of the turn table to direct the dirt turned up by the plow on to said turn table, the plow being secured in this position by bars 37 extending upward therefrom for 30 securing to the track frame 22, whereby free rotation of the turn table relative to the plow is permitted. Also carried by arms 38 extending downwardly and outwardly from the track frame 22 is a scraper plate 39 which overlies the peripheral portion of 35 the turn table and is adapted to scrape dirt from said turn table upon rotation of the turn table, to deposit said dirt at the side of the machine. Thus upon forward movement of the machine and rotation of the 40 turn table, dirt will be deposited on the turn table by the plow at one side of the machine and will be carried to the other side of the machine and there discharged by the plate 39.

45 For effecting this rotation of the turn table, in a manner readily permitting the described adjustments thereof, a gear wheel 40 is carried by one of the ground wheels 16 of the rear axle 13, and meshes with a pinion 41 on the rear end of a shaft 42 extended longitudinally under one of the sills 10 and journaled in hanger bearings 43 depending therefrom. A second shaft 44 is journaled in hanger brackets 45 depending from the horizontal forward portion and 55 the sills of these shafts, which are thus disposed in angular relation, are connected by a universal coupling 46. The shaft 44 extends a considerable distance forwardly of the turn table and has fixed on its forward end a beveled gear 47 meshing with a gear 48 carried on the shaft 49 also journaled in the forward hanger bearing 45 and extending obliquely with respect to the shaft 44. The rear end of the shaft 49 is connected by 60 a universal coupling 50 with one end of a

tubular shaft section 51 in which is telescopically slideable a shaft section 52 which is squared to fit into correspondingly squared recesses of the shaft 51 or transversely connected with the shaft 51 in a 70 manner insuring driving rotation thereof by said shaft 51. The shaft section 52 is connected by a universal coupling 53 with a shaft 54 mounted in a bearing 55 upstanding from the track frame 22 adjacent its central 75 portion. This shaft 55 carries a beveled gear 56 meshing with a beveled gear 57 on the upper end of a shaft 58 which is journaled in and extended through the track frame 22, and rigidly connected with the 80 turn table.

The tilting movement to which the shaft 54 carried by the track frame is subjected during adjusted tilting movement of the track frame is thus compensated for by the 85 universal couplings 50 and 53, and the extensible shaft line formed by the sections 51 and 52.

Reviewing now the general operation of the machine for procuring a proper transverse grading or crowning of the road way, it is drawn along the road to dig a furrow by the plow 36, and the dirt from said furrow is discharged on to the turn table and carried to the opposite side of the machine, where it is discharged on to the ground by the scraper plate 39. The machine is then drawn over the same stretch of road way to dig a second furrow in the longitudinal portion of the road way which is to 100 be lowered, it being noted that the general operation of the machine is very similar to a simple plow operation with the exception that the earth turned by the moldboard of the plow is discharged a greater distance 105 away laterally of the plow. The grading operation is usually started at one side of and adjacent the center of the road way, to deposit the dirt taken from the first furrows onto the center of the road way, the 110 machine being moved in successive operations toward the side of the road to procure proper depression thereof.

By tilting the turn table in the manner described, the depth of the furrow dug by the plow may be varied, it being noted that at all times the adjacent edge of the turn table approximates the bottom of the furrow whereby to receive a maximum discharge of earth thereonto.

115 If desired, a pair of turn tables 35^a and 35^b of two machines may be placed side by side as shown in Figs. 9 and 10, with the plow of one machine removed and the corresponding side portion of its turn table disposed under the side portion of the other turn table which carries the plate 39. Thus upon propulsion of a pair of machines arranged in this manner, the dirt dug by the 120 plow of one machine will be carried trans- 125 130

versely of both machines and deposited on the ground at a relatively greater lateral distance from the furrow.

What is claimed is:

- 5 1. In a road grading machine, a framework, a circular track carried thereby, a turn table rotatably supported by and below the track, a suspension member depending from the framework, a longitudinal pivot connecting it with the track, a pair of bars pivotally connected with lateral portions of the track, and means carried by the framework for adjusting said bars vertically and independently to rock the track on its pivot.
- 10 2. In a road grading machine, the combination with a framework mounted on wheels, a hand-operated gear on the framework, a track mounted on a longitudinal pivot beneath the framework, and a rack bar rising from the side of said track and engaged by said gear; of a rotary turn table supported by and below the track, a plow supported by the track at one side of and beyond the turn table, and a scraper supported by the track 25 and resting on the turn table opposite the plow.

3. In a road grading machine, the combination with a framework mounted on wheels, a circular track beneath the framework, a support depending from the framework and connected by a longitudinal pivot with the forward portion of the track, posts rising from the rearward portion of the track near its lateral sides, and means on the framework for raising and lowering said posts independently; of a turn table rotatably carried by the track and driven from one of the main wheels, a plow supported by the track at one side of and beyond the turn table, and a scraper supported by the track and resting on the turn table opposite the plow.

4. In a road grading machine, the combination with a framework mounted on wheels, a circular track beneath the framework, a support depending from the framework and connected by a longitudinal pivot with the forward portion of the track, posts rising from the rearward portion of the track near its lateral sides, aligned shafts supported by said framework and carrying independent gears and hand wheels, and rack bars pivoted to said posts and meshing with the respective gears; of a turn table rotatably carried by the track and driven from one of the main wheels, a plow supported by the track

at one side of and beyond the turn table, and a scraper supported by the track and resting on the turn table opposite the plow.

5. In a road grader of the type described, 60 the combination with an annular track frame having a depending marginal flange inturned into a circular track, a wheeled framework, and means for adjustably supporting the track frame beneath the framework; of a turn table comprising a plate beneath and larger than said frame, brackets rising therefrom into the frame and turned outward, rollers on the brackets traveling on said track, means connected with one 70 driving wheel for rotating said turn table, a plow supported by the track at one side of and beyond the turn table, and a scraper supported by the track and resting on the turn table opposite the plow. 75

6. In a road grader of the type described, the combination with an annular track frame having a depending marginal flange inturned into a circular track, a wheeled framework, and means for adjustably supporting the track frame beneath the framework; of a turn table comprising a plate beneath and larger than said frame, brackets rising therefrom into the frame and turned outward, rollers on the brackets traveling 80 on said track, a shaft rising from the turn table through the center of the frame, gearing connections between it and one main driving wheel, said connections permitting the adjustment of the track frame, and 85 means carried by the track frame for collecting earth and depositing it on one side of the turn table and for removing it from the opposite side. 90

7. In a machine of the type described, a 95 pair of horizontally disposed turn tables overlapping at their inner edges and rotated in the same direction, a plow at the outer side of the upper turn table for gathering earth and depositing it thereon, a scraper 100 above the inner side of this turn table for delivering the earth to the lower turn table, and a scraper at the outer side of the lower turn table for delivering the earth therefrom, the whole for use as hereinbefore set 105 forth.

In testimony whereof, I affix my signature, in the presence of two witnesses.

(Mr.) CHARLIE SPETH.
